UNITED STATES PATENT OFFICE.

ISAAC S. MACKIE, OF NEW YORK, N. Y.

GOLF-CLUB.

1,098,630.

Specification of Letters Patent. Patented June 2, 1914.

Application filed February 5, 1914. Serial No. 816,720.

To all whom it may concern:

Be it known that I, ISAAC S. MACKIE, a subject of the King of Great Britain, and a resident of the borough of Richmond, in the city and State of New York, have invented certain new and useful Improvements in Golf-Clubs, of which the following is a specification.

My invention relates particularly to improvements in wooden headed golf clubs, of the kind known as "drivers" or "brassies." A club of this type is used to drive a golf ball over long distances. In order that the club shall satisfactorily perform its function and drive the ball with accuracy the shaft thereof should be resilient close to the head, and the head should be firmly and rigidly united to the shaft in such a manner as to prevent it from twisting.

Heretofore clubs have been constructed with shafts of hickory or other suitable resilient wood which are tapered at the portion adjacent to the head and joined thereto by inserting and gluing the lower end of the shaft into a socket formed in the head. While a club thus made complies with the first of the above-named conditions, it is deficient in that it does not satisfy the second. When such a club is driven against the ball with considerable force, as is necessary in making a long drive, the head thereof will tend to twist or turn around the shaft, particularly if the ball is struck by the toe or forward part of the head, and thus cause the ball to "slice" or travel at a tangent to the direct line of aim. Attempts have been made to remedy this defect by fastening the head directly to the shaft by means of a scarf or spliced joint. As, however, the head is generally made of a stiff and non-resilient wood, such a joint will diminish the resiliency of the combined structure and while the club will permit of accurate placing or driving of the ball, it will not permit of drives of as great a length as with a club having greater resiliency.

The principal object of my invention is to provide a club having a shaft composed of two pieces which is resilient at the portion adjacent to the head and having the head firmly and rigidly united to the shaft so as to enable the player to combine "distance" with "accuracy" of drive.

In the accompanying drawings illustrating my invention, Figure 1 is a longitudinal section through the head and lower part of

the shaft of a club embodying my invention. Fig. 2 is a cross section taken on the line *a—a* of Fig. 1; and Fig. 3 is a fragmentary rear view of a club, with the winding removed, showing the joint between the shaft and the head.

Referring to the preferred embodiment of my invention shown in the drawings, 1 is the head of a club having an elongated neck 2 and provided with a socket 3, extending through the neck and into the head. The upper rear portion of the wall of the neck is beveled slightly inwardly as at 4, in Fig. 1.

The shaft is composed of two pieces of hickory or other suitable strong and flexible wood shaped in the usual manner so as to have resiliency along the portion thereof adjacent to the head. Said shaft consists of a main stick 5 having its lower end beveled crosswise and tapered longitudinally and united, in the form of a scarf or spliced joint 7, to the beveled upper end of the piece 6, the lower extremity of which fits snugly into the socket 3 of the head.

The tip or lower extremity of the piece 5 extends beyond the joint 7 and overlaps the beveled portion 4 of the rear wall of the neck 2, as best seen in Fig. 3, so as to provide a structure whereby the head is firmly held in a manner to prevent it from twisting or turning around the longitudinal axis of the shaft upon impact against the ball.

The several parts are cemented together with glue or other suitable adhesive material and are bound or reinforced by means of a cord or tape winding 8 covering the parts.

By means of the construction herein described, I provide a golf club which has sufficient resiliency to enable it to be used for making a long drive and in which the head is firmly held so as to secure accuracy of drive.

While I prefer to secure the head to the shaft by gluing the extremity of the shaft into a socket formed in the head, as shown herein, any other suitable manner of uniting said parts may be employed.

What I claim as my invention and desire to secure by Letters Patent is:

1. A golf club comprising a shaft consisting of two joined pieces of wood, a head secured to one of said pieces and having the lower extremity of the other piece overlapping a portion of the head.

2. A golf club comprising a shaft having a piece of wood spliced to the lower end thereof, a wooden head fastened to the spliced piece and having the lower extremity of the shaft overlapping the head.

3. A golf club comprising a shaft consisting of two pieces of wood united in a scarf joint and having the tip of one of said pieces extending beyond the joint, a wooden head secured to the lower end of the shaft

with the extended tip thereof bearing against the upper rear portion of the head. In testimony whereof, I have signed my name to this specification, in the presence of two subscribing witnesses.

ISAAC S. MACKIE.
